(57) **CLAIM**

We claim the ornamental design for a flexible garment for supporting a small portable electronic device, as shown and described.

DESCRIPTION

FIG. 1 is a front view of a first form of our new design, and includes a depiction of a transparent pocket portion for containing a small portable electronic device;

FIG. 2 is a right side view thereof;

FIG. 3 is a rear view thereof;

FIG. 4 is a left side view thereof;

FIG. 5 is a top view thereof;

FIG. 6 is a bottom view thereof;

FIG. 7 is a front view of a second form of our new design that is identical in shape and construction to the first form, with portions lined to indicate color contrasting surface areas that exhibit different colors or at least light-reflective characteristics that differ from each other;

FIG. 8 is a right side view thereof;

FIG. 9 is a rear view thereof;

FIG. 10 is a left side view thereof;

FIG. 11 is a top view thereof; and,

FIG. 12 is a bottom view thereof.

Portions broken away or not shown form no part of the claimed design. No appearance feature of any part of the garment located behind a transparent window shown in FIGS. 1 and 7 is claimed. Areas in FIGS. 8-12 that are lined to indicate color contrast may exhibit different colors or different light-reflective characteristics.

Because the garment is flexible, those skilled in the art will appreciate that configurations exhibited by the garment are likely to vary depending, at least in part, on how the garment is worn, positioned or supported.
